UNITED STATES PATENT OFFICE.

JAMES G. DEMAREST, OF WEST HOBOKEN, NEW JERSEY, ASSIGNOR TO
CLARA A. BAKER, OF NEW YORK, N. Y.

HOT-WATER HEATING SYSTEM.

No. 821,991.

Specification of Letters Patent.

Patented May 29, 1906.

Application filed July 7, 1904. Serial No. 215,600.

To all whom it may concern:

Be it known that I, JAMES G. DEMAREST, a citizen of the United States, residing in West Hoboken, county of Hudson, and State of New Jersey, have invented certain new and useful Improvements in Hot-Water Heating Systems, of which the following is a full, clear, and exact specification.

My invention relates to hot-water heating systems, and particularly to that character of apparatus such as is usually employed for heating railroad-cars and the like, wherein a heating-coil is provided in operative contact with a coal fire or other source of heat and radiating-pipes extend from said coil throughout the car for carrying the heated fluid to places remote from the heater proper. In such systems it has been usual to employ a steam-jacket around a portion of the pipes, obtaining steam from the locomotive, and thus the heating fluid may be caused to circulate in the pipes without the necessity of a coal fire in the stove or heater proper. In these systems, however, it has required a considerable time to produce a complete circulation of the fluid after building fire in the heater or turning on the steam, owing to the increasing amount of piping required to fit out the more modern and very long cars, and it is this slowness in getting them under way that my invention is designed to obviate.

In the accompanying drawings, illustrating one form of my invention, I have shown a diagrammatic arrangement of pipes, it being understood that the disposition thereof is shown conventionally only.

In the drawings, 1 represents the heater-coil, which may be of any well-known type. To the lower end of this coil is connected by a suitable joint the return-pipes 2 3 of the circuits A and B. To the upper ends of the coil by a similar divided connection are attached the riser-pipes 4 5, carrying steam-jackets or steam-heaters 6 and 7 of any well-known type, the sectional view of the jacket 6 showing the preferable form which is fully shown in United States Letters Patent No. 498,924, granted to William C. Baker June 6, 1893, and which therefore need not be herein more particularly described. From the upper end of each steam-jacket is provided the pipes 8 and 9, leading into the expansion-drums 10

and 11, and from said expansion-drums pipes 12 and 13 lead to the radiating-pipes of each separate circuit around the car and back to the bottom of the heating-coil. It will thus be seen that in my system I have two complete circulating systems, while utilizing but one heating-coil in the coal-burning heater, and by dividing the circuits in this manner the heated fluid has but half of the distance to travel, and I have found that a given-sized coil will produce a complete circulation in each branch in less than one-third of the time it takes to force the fluid through the same length of pipe were it in one continuous circuit.

When it is desired to operate the system by the steam-heaters alone, it is unnecessary to require the two circuits to pass through the coil, and I have, therefore, provided a shunt-pipe 14, which connects the return of the system B to the lower end of the steam-heater 7, and by closing valves 15 and 16 and opening valve 17 the systems A and B are made substantially independent and distinct, as shown in the drawings. It is possible, however, and in some instances it may be desirable, to so arrange the piping that systems A and B will not be entirely independent, but be connected in series when valves 15 and 16 are closed—that is, the water circulated from the system A will return to the bottom of system B, where it is subjected to the action of the heater 7 and is forced through the system B back to the bottom of system A. The main steam service-pipe 18 supplies steam to steam-heaters 6 and 7 through branches 19 and 20, having valves 21 and 22.

I have found that when operating the circulation in systems of this character it is advantageous to relieve any pressure which may be created at the inception of the operation; but care must be taken that no water is allowed to escape. To obtain this result, I provide the air-vents or relief-pipes 23 and 24, connected to the safety-vents 25 and 26, so as to be above the possible water-line in the drum, and by keeping the valves 27 and 28 open until the circulation has been completed and then closing them I have an ideal result.

It is obvious that many modifications and

changes may be made in the general form of my invention without departing from the spirit thereof, and I do not intend to limit myself to the particular mechanism and arrangement shown and described; but

5 What I claim, and desire to secure by Letters Patent, is—

1. In a hot-water heating system, a plurality of independent water-circulating circuits, each of said circuits including expansion means, a heating-coil included in one of said circuits, with means for bringing said coil into communication with the other circuit, and an independent steam-heating attachment in operative connection with each of said circuits, whereby each of said circuits may be operated independently or they may all be heated by the said heating-coil, substantially as described.
- 10 2. In a hot-water heating system, two independent circulating-circuits, each of said circuits including an independent expansion vessel, a heating-coil included in one of said independent circuits with means for bringing said coil into communication with the other circuit, and a separate steam-heater for operating each of said circuits, whereby each circuit may be operated independently or they may both be operated by said heating-coil, substantially as described.
- 15 3. In a hot-water heating system two independent circulating-circuits, each of said circuits including an independent expansion vessel, a heating-coil included in one of said independent circuits with means for bringing said coil into communication with the other circuit, and a separate steam-heater above the coil for operating each of said circuits whereby each circuit may be operated independently or they may both be operated by said heating-coil, substantially as described.
- 20 4. In a hot-water heating system, two independent circulating-circuits, each of said circuits including an independent expansion vessel, a single heating-coil included in one of said independent circuits with means for bringing said coil into communication with the other circuits, and a shunt-pipe in such other circuit around the coil, an independent steam-heater for operating each of said circuits, whereby each of said circuits may be operated independently or they may both be operated by said coil, substantially as described.
- 25 5. In a hot-water heating system, two independent circulating-circuits, each of said circuits including an expansion vessel, a single heating-coil included in one of said independent circuits with means for bringing said coil into communication with the other circuit, and a shunt-pipe in such other circuit around the coil, an independent steam-heater located above the coil for operating each of said cir-

cuits, whereby each of said circuits may be operated independently or they may both be 65 operated by the said coil, substantially as described.

6. In a hot-water heating system, a plurality of water-circulating circuits, each of said circuits including expansion means, a single 70 coil included in one of said circulating-circuits, and means for bringing said coil into communication with the other circuit, an independent steam-heating attachment upon each of said circuits, whereby each of the said circuits may be operated independently or they may both be operated by the said coil, and an air-vent connecting the highest points in the system, substantially as described.

7. In a hot-water heating system, two independent circulating-circuits, each of said circuits including an expansion vessel, a single coil included in one of said independent circuits, and means for bringing said coil into communication with the other circuit, an independent steam-heater for operating each of said circuits whereby the said circuits may be operated independently of the said coil, or they may both be operated by the said coil, and an air-vent connecting with the highest 85 points in the system, substantially as described.

8. In a hot-water heating system, two independent circulating-circuits, each of said circuits including an expansion vessel, a single 90 coil included in one of said independent circuits, and means for bringing said coil into communication with the other circuit, an independent steam-heater for operating each of said circuits located above the coil, whereby 100 the said circuits may be operated independently of the said coil, or they may both be operated by the said coil, and an air-vent connecting with the highest points in the system, substantially as described.

9. In a hot-water heating system, two independent circulating-circuits, each of said circuits including an expansion vessel, a single coil included in one of said independent circuits, and means for bringing said coil into communication with the other circuit, a shunt-pipe in such other circuit around the coil, and an independent steam-heater for operating each of said circuits, whereby the said circuits may be operated independently of the said coil, or they may both be operated by the said coil, and an air-vent connecting with the highest points in the system, substantially as described.

10. In a hot-water heating system, two independent circulating-circuits, each of said circuits including an expansion vessel, a single coil included in one of said independent circuits, and means for bringing said coil into communication with the other circuit, a 120 shunt-pipe included in such other circuit

around the coil, an independent steam-heater located above the coil for operating each of said circuits whereby the said circuits may be operated independently of the said coil, or 5 they may both be operated by the said coil, and an air-vent connecting with the highest points in the system, substantially as described.

In testimony whereof I have hereunto set my hand in the presence of two subscribing witnesses.

JAMES G. DEMAREST.
